US0D1046079S

(12) **United States Design Patent** (10) **Patent No.:** **US D1,046,079 S**
(45) **Date of Patent:** **** Oct. 8, 2024**

(54) **FAUCET**

(71) Applicant: **Buster and Punch Limited**, Stamford (GB)

(72) Inventor: **Massimo Minale**, London (GB)

(73) Assignee: **Buster and Punch Limited**, Stamford (GB)

(**) Term: **15 Years**

(21) Appl. No.: **29/822,554**

(22) Filed: **Jan. 10, 2022**

(30) **Foreign Application Priority Data**

Aug. 2, 2021 (GB) 6152043
Aug. 2, 2021 (GB) 6152044

(57) **CLAIM**

The ornamental design for a faucet, as shown and described.

DESCRIPTION

FIG. 1 is an isometric view of a faucet showing a first embodiment of the design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is an isometric view of a faucet showing a second embodiment of the design.

FIG. 9 is a front elevation view thereof.

FIG. 10 is a rear elevation view thereof.

FIG. 11 is a left side elevation view thereof.

FIG. 12 is a right side elevation view thereof.

FIG. 13 is a top plan view thereof; and,

FIG. 14 is a bottom plan view thereof.

The dash-dot lines in the drawings represent or bound portions of the design that are not claimed. The dashed lines in the drawings represent portions of the design that are not claimed.

1 Claim, 14 Drawing Sheets
